UNITED STATES PATENT OFFICE

146,011

DESIGN FOR A RADIO RECEIVER

Frederick D. Schnoor, Stratford, Conn., assignor
to General Electric Company, a corporation of
New York

Application November 24, 1945, Serial No. 124,048

Term of patent 14 years

(Cl. D56—4)

To all whom it may concern:

Be it known that I, Frederick D. Schnoor, a citizen of the United States, residing at Stratford, in the county of Fairfield, State of Connecticut, have invented a new, original, and ornamental Design for Radio Receivers, of which the following is a specification, reference being had to the accompanying drawings, forming a part thereof.

Fig. 1 of the drawings shows my new design of radio receiver with the cover closed and Fig. 2 shows my new design of radio receiver with the cover open. The rear and other end surfaces of the receiver are unornamented.

I claim:

The ornamental design for a radio receiver, as shown and described.

FREDERICK D. SCHNOOR.
